UNITED STATES PATENT OFFICE.

GEORGE W. JORDAN, OF WORCESTER, MASSACHUSETTS, ASSIGNOR TO
KNOWLTON & BEACH, OF ROCHESTER, NEW YORK.

MACHINE FOR SCORING CARDBOARD.

SPECIFICATION forming part of Letters Patent No. 621,965, dated March 28, 1899.

Application filed May 18, 1896. Serial No. 591,902. (No model.)

To all whom it may concern:

Be it known that I, GEORGE W. JORDAN, a citizen of the United States, residing at Worcester, in the county of Worcester and 5 State of Massachusetts, have invented a new and useful Improvement in Machines for Scoring Cardboard, of which the following is a specification, reference being had to the accompanying drawings, forming a part of the 10 same, in which—

Figure 1 represents a top view of a scoring-machine embodying my invention. Fig. 1^a shows a portion of one of the feed-tables with a guide-rib attached thereto, forming the way 15 or track for the pushing-plate. Fig. 2 represents a side view of the upper part of the machine, the lower portion of the supporting-framework being omitted. Fig. 3 is an end view of the upper part of the machine, shown 20 in sectional view on line 3 3, Fig. 2. Fig. 4 is an end view of a portion of the machine, shown on a larger scale and showing the eccentric by which a reciprocating motion is given to the second pushing-plate, the shaft carrying 25 said eccentric being shown in sectional view on line 4 4, Fig. 2. Fig. 5 is a central sectional view on line 5 5, Fig. 4, of the clamping device for supporting the horizontal retaining-plates arranged over the second feed-table. 30 Fig. 6 is an end view of the adjustable stop for limiting the forward movement of the cardboard on the second feed-table and for holding it against any rebound or forward movement. Fig. 7 is a central vertical sectional 35 view of the same on line 7 7, Fig. 6. Fig. 8 is a side view of one of the adjustable cutters. Fig. 9 is an end view of the same. Fig. 10 is a central sectional view on line 10 10, Fig. 9. Fig. 11 represents portions of the two scor- 40 ing-rolls with portions of the first and second feed-tables on an enlarged scale, showing the spring-actuated pressure-plate in vertical sectional view, by which the cardboard is held down as it passes to the first scoring mechan- 45 ism, and also showing portions of the tripping mechanism by which the movement of the cardboard onto the second feed-table is made to control the reciprocating movement of the second pushing-plate. Said Fig. 11 also shows 50 one of the guide-plates by which the strip cut from the edge of the cardboard, in order to

trim the same, is diverted and carried below the second feed-table. Fig. 12 is a top view of a portion of the spring-actuated pressure-plate, certain parts being shown in sectional view in order to disclose the torsional spring by which the pressure-plate is held upon the cardboard with a yielding pressure. Fig. 13 is an edge view of the second feeding-table with the guide-plates for turning the strips 60 cut from the sides of the cardboard beneath the table. Fig. 14 is a perspective view of the guide-plate attached to the edge of the second feed-table next the scoring-roll for turning the severed strip of cardboard beneath the 65 table. Fig. 15 is a perspective view of the guide-plate attached to the edge of the second feed-table farthest from the second scoring-roll, and Fig. 16 is a central sectional view of the eccentric for moving the pushing-plate 70 and clutching mechanism.

Similar letters refer to similar parts in the different figures.

My invention relates to certain improvements in that class of scoring-machines which 75 comprise two scoring mechanisms for the purpose of scoring a sheet of cardboard in two directions at right angles to each other to allow the cardboard to be bent on its scored lines in the manufacture of a paper box, the 80 machine embodying my present invention being what is known as a "double-scoring" machine; and my present invention consists in certain features of construction and arrangement of parts, as hereinafter described, and 85 specifically pointed out in the annexed claims, by which certain advantages are secured, such as simplicity of construction, efficiency and accuracy of operation, and automatic control of the cardboard, as hereinafter set 90 forth.

Referring to the drawings, A denotes the first feed-table, upon which a sheet of cardboard is fed to the first scoring mechanism, it being pushed forward on the table A by 95 hand by means of a pushing-plate A', projecting laterally from a sliding plate A², which slides upon and is guided by the vertical member A³ of an angle-plate A⁴, adjustably attached to the feed-table A by a tightening-bolt A⁵.

The first scoring mechanism consists of a

bed-roll A⁶ and rotating cutters A⁷, held in frames A⁸, adjustably attached to the under side of a cutter-bar A⁹, which is journaled at its ends in the framework of the machine in order to allow it to be rotated to raise the rotating cutters into convenient position for adjustment, said cutter-bar A⁹ being held from rotation during the operation of the machine by a sliding bolt A¹⁰ in lugs projecting from the side of the cutter-bar, with its end carried by the springs A¹¹ into a hole in the framework of the machine. The sliding bolt A¹⁰ is withdrawn to allow the cutter-bar to be rotated by means of the pivoted lever-handle A¹² A¹³.

As the sheet of cardboard passes from the feed-table A over the bed-roll A⁶ it passes beneath a pressure-plate A¹³. (Shown in sectional view and on a larger scale in Figs. 11 and 12.)

The pressure-plate A¹³ consists of a curved sheet-metal plate provided at its upper edge with gudgeons A¹⁴ A¹⁴, which are journaled in a sleeve A¹⁵, held in and capable of being slightly rocked in the forked ends of the brackets A¹⁶, which project from the framework of the machine. The sleeves A¹⁶ are provided with the tailpieces A¹⁷, which extend between adjusting-screws A¹⁸ A¹⁹, held in lugs projecting from the brackets A¹⁶, the adjustment of the screws serving to rock the sleeves A¹⁵ slightly within their forked bearings, so as to change the position of the pressure-plate A¹³ and vary the distance between the lower edge A²⁰ of the pressure-plate and the bed-roll A⁶.

Flanged collars A²¹ are attached to the gudgeons A¹⁴ by set-screws A²² and inclose torsional springs A²³, one of which is shown in Fig. 12. One end of the torsional spring A²³ engages the collar A²¹, and the opposite end engages the sleeve A¹⁵, so the tension of the spring will be exerted to prevent the rocking of the gudgeons A¹⁴ in their bearings by the rising of the lower end A²⁰ of the pressure-plate A¹³. The adjustment of the collars A²¹ on the gudgeons A¹⁴, by means of their attaching set-screws, allows the tension of the torsional springs A²³ to be varied. By loosening one of the adjusting-screws A¹⁸ or A¹⁹ the sleeves A¹⁵, together with the pressure-plate A¹³, can be readily removed from the forked end of the brackets A¹⁶, the sleeves being held in place by the adjusting-screws A¹⁸ and A¹⁹, which enter countersunk recesses in the tailpieces A¹⁷. The sheet of cardboard is scored in one direction in the usual manner by the action of the bed-roll A⁶ and cutters A⁷ and is moved by them forward onto the second feed-table B, which is slightly lower than the first feed-table A. The two outer cutters in the first scoring mechanism serve to trim the opposite edges of the cardboard, the cutter on the right cutting off a narrow strip of the cardboard sufficient to straighten its edge and the cutter on the left cutting the

cardboard the proper width required for the box, while two intermediate cutters score the cardboard in two parallel lines, upon which the cardboard is to be bent to form the sides of the box. The strips which are cut off from the sides of the cardboard are deflected and carried beneath the table B by means of guide-plates B' and B², which are attached to the edge of the table B and are represented in perspective view in Figs. 14 and 15. The guide-plates B' and B² are attached to the edge of the table B and extend partially over the bed-roll A⁶, with their free ends slightly raised above the surface of the roll to allow the severed strip of cardboard to pass beneath them.

The guide-plate B' upon the right-hand side of the cardboard is provided with the depending sides B³ B³, between which the narrow strip of cardboard severed from the sheet passes. Upon the inner sides of the guide-plates B' and B² are the horizontal blades B⁴, which support the side edges of the cardboard between the bed-roll A⁶ and the edge of the table B and insure its passage upon the table.

The under side of the edge of the table B next the bed-roll A⁶ is provided with a triangular rib B⁵, which is notched at B⁶, and the guide-plates B' and B² are provided with the hooked prongs B⁷, which extend beneath the triangular rib B⁵ and are drawn against it by binding-screws B⁸, the notch B⁶ allowing the hooked prong B⁷ to be inserted and the guide-plate to be locked upon the triangular rib by being moved to the right or left of the notch B⁶.

Arranged a short distance above the surface of the table B are a series of horizontal retaining-plates B⁹, extending transversely across the table B parallel with the movement of the cardboard, with one end slightly raised, as at B¹⁰, Fig. 11, to project partially over the scoring-roll A⁶, so the sheet of cardboard as it passes upon the table B will be conducted beneath the retaining-plates B⁹.

The retaining-plates B⁹ are provided near their opposite ends with the hollow stems B¹¹, which inclose the spindles B¹², depending from the clamping-bars B¹³ and B¹⁴. The retaining-plates B⁹ are capable of a slight vertical movement by the hollow stems B¹¹ sliding upon the spindles B¹², with which they are connected by means of pins B¹⁵, held in the spindles B¹² and entering slots B¹⁶ in the hollow stems B¹¹, thereby holding the plates B⁹ parallel with the face of the table as they rise and fall upon the spindles B¹². The spindles B¹² are adjustably connected by the clamping-bars B¹³ and B¹⁴ with horizontal rods B¹⁷, which are supported above the table B by posts at the corners of the table. The clamping-bars are connected at one end by an elastic plate B¹⁸, and their opposite ends are recessed at B¹⁹ to inclose the supporting-rods B¹⁷.

The spindles B¹² have a fixed collar B²⁰ bearing against the lower clamping-bar B¹³ and a nut B²¹ held upon the screw-threaded end of

the spindle B¹² and bearing against the upper side of the clamping-bar B¹⁴, allowing the bars to be pinched upon the rod B¹⁷.

5 The spiral spring B²² is inserted between the clamping-bars B¹³ and B¹⁴ in order to separate them and release the rod B¹⁷ when the nut B²¹ is unscrewed.

10 The retaining-plates B⁹ consist of broad steel plates held at a slight distance above the surface of the table B in order to retain the sheet of cardboard in a horizontal plane when acted upon by the pusher-plate B²³, which consists of a thin blade capable of passing between the surface of the table and the 15 retaining-plates B⁹. The pusher-plate B²³ is attached at one end to a sliding plate B²⁴, sliding in ways B²⁵ at the side of the table B and outside of the surface occupied by the cardboard.

20 The slide B²⁴ has a depending lug B²⁶, Fig. 3, projecting beneath the table and pivoted to one end of a lever B²⁷, which is pivoted at its opposite end to a bracket B²⁸ and midway its length to a rod B²⁹, connecting it with the 25 strap B³⁰ of an eccentric B³¹, which is carried upon a shaft B³², upon which is mounted the second scoring-roll B³³, so one revolution of the eccentric will impart a complete reciprocating motion forward and backward to the 30 pusher B²³, carrying the sheet of cardboard upon the second feed-table B forward to be engaged by the second scoring mechanism, comprising the bed-roll B³³ and the rotating cutters B³⁴, attached to the cutter-bar B³⁵.

35 The eccentric B³¹ is rotated at the proper period of time by a clutching mechanism, which is thrown into action by means of a tripping mechanism actuated by the moving sheet of cardboard and comprising a finger C, Fig. 11, 40 depending from a rocking sleeve C', supported on one of the rods B¹⁷. The sleeve C' is provided with a radial arm C², connected by a link C³ with a lever C⁴, pivoted at C⁵ to a fixed support and having its opposite end 45 pivotally connected with a vertical rod C⁶, extending downward at the end of the machine and connected with the toggle-joint levers C⁷ and C⁸, connecting the lower end of the rod C⁶ with the framework of the machine.

50 The vertical rod C⁶ is capable of a slight swinging motion on the end of the lever C⁴, and the toggle-joint connection of the lower end of the rod C⁶ is for the purpose of causing the lower end of the rod to swing by the straightening of the levers C⁷ and C⁸, as hereinafter described.

55 As the cardboard passes from the first scoring mechanism onto the second feed-table B its advancing edge strikes against the finger C, rocking the sleeve C' and raising the connected end of the lever C⁴, and as soon as the cardboard passes the finger C the finger is carried back to its normal position and the 60 motion of the lever C⁴ is reversed by means of a pull-spring C⁹, connecting the end of the lever C⁴ with the fixed framework of the ma-

chine. The vertical rod C⁶ passes through an opening in a horizontal latch C¹⁰, pivoted at one end at C¹¹ to a bracket depending from the under side of the table B. The free end of the latch C¹⁰ is provided on its under side with a wedge-shaped lug C¹², adapted to drop into an annular groove C¹³ in the hub of the eccentric B³¹, and the latch C¹⁰ is pressed 75 downward by a spring C¹⁴, inserted between the latch and the table B.

The shaft B³², upon which the eccentric B³¹ turns loosely, carries an attached gear-wheel C¹⁵, by which the shaft B³² is rotated by its 80 engagement with the pinion C¹⁶, carried on a main driving-shaft C¹⁷, which is journaled in brackets at the side of the machine. The hub of the gear-wheel C¹⁵, on the side next the eccentric B³¹, is provided with clutch-teeth C¹⁸, which are adapted to be engaged by a sliding clutch-bar C¹⁹, sliding in a groove in the hub of the eccentric B³¹ and arranged to be pushed outward to engage the clutch-teeth C¹⁸ by a spring C²⁰. The sliding clutch-bar C¹⁹ is provided with a notch C²¹ in proper position to be caught by the pointed end of the wedge-shaped lug C¹² as the eccentric is rotated, thereby causing the sliding clutch-bar to be withdrawn from its engagement 90 with the clutch-teeth C¹⁸. The vertical rod C⁶ is provided with a shoulder C²², which is adapted to strike the under side of the latch C¹⁰ when the rod C⁶ is raised and lift the latch, withdrawing its wedge-shaped lug C¹² from the annular groove C¹³ in the hub of the eccentric B³¹, thereby allowing the spring C²⁰ to force the sliding clutch-bar C¹⁹ into engagement with the clutch-teeth C¹⁸ and causing the rotary motion of the gear C¹⁵ to be 95 imparted to the eccentric. Attached to the lower end of the rod C⁶ and at right angles thereto is an arm C⁷, which is pivotally connected with the frame by means of a link C⁸, and when the rod C⁶ is in its lowest position 100 the arm C⁷ and link C⁸ are in the position shown in Figs. 3 and 17, with the arm C⁷ and link C⁸ forming an angle with each other; but when the rod C⁶ is raised the arm C⁷ and link C⁸ are lifted, bringing the link C⁸ into a 105 straight line with the arm C⁷, as shown in Fig. 18, thereby moving the lower end of the vertical rod C⁶ to one side and carrying the shoulder C²² out of engagement with the under side of the latch C¹⁰. The opening in the 110 latch is large enough to allow the shoulder C²² to pass thereby, thereby releasing the latch C¹⁰, which is instantly forced down by the spring C¹⁴, carrying the wedge-shaped lug C¹² into the annular groove C¹³ in position to engage the notch C²¹ of the sliding clutch-bar and withdraw the same from its engagement 115 from the clutch-teeth C¹⁸, thereby stopping the eccentric at the end of one complete revolution.

120 By the action of the above-described mechanism the movement forward of the sheet of cardboard upon the table B will swing the finger C, and carry the rod C⁶ downwardly 125

without engaging the latch C¹⁰; but when the finger C is released by the passage of the cardboard beneath it the spring C⁹ reverses the movement of the finger C and raises the vertical rod C⁶, when the shoulder C²² of the rod C⁶ hits the latch and lifts it, allowing the sliding clutch-bar to engage the clutch-teeth C¹⁸.

The driving-shaft C¹⁷ carries the belt-pulley C²³, running loosely thereon, but capable of being connected with the driving-shaft by a clutch mechanism C²⁴, of the usual and well-known form of construction, which is thrown into and out of engagement by means of a 15 shipping-lever C²⁵, links C²⁶, and bell-crank lever C²⁷. (Shown by broken lines in Fig. 1 beneath the table A in convenient position to be operated by the attendant.) The first scoring-roll A⁶ is rotated from the driving-shaft 20 C¹⁷ by means of the beveled gears C²⁸ C²⁹. Projecting from the lower side of the pusher-slide B²¹ is a lug D, which carries a rod D', sliding through the fixed lug D², attached to the under side of the table B and carrying an adjustable collar D³, between which and the fixed lug D², I insert a compression-spring D⁴, which acts as a buffer to check the momentum as the pusher B²⁴ and B²⁵ is pushed outward.

Supported a short distance above the upper 30 surface of the table B are the parallel rods E E, upon which are placed sliding sleeves E' E', adjustably attached by set-screws to the rod E, and supported by the sleeves E' E' is a rod E², to which the device for stopping the movement of the cardboard on the table B is 35 adjustably attached, said stop device consisting of a sleeve F, having a spline connection with the rod E² and held from longitudinal movement on the rod and in any desired position by means of a set-screw F'. The sleeve F is provided on opposite sides with the gudgeons F² F³, and on the gudgeon F² is suspended the swinging frame F⁴, provided with holes F⁵ F⁵ in its lower end, in which are placed the 40 sliding pins F⁶ F⁶, which are pressed downward by spiral springs F⁷ F⁷, and the lower ends of the pins F⁶ carry a pin F⁸, upon which the roll F⁹ turns. The roll F⁹ is slightly beveled, and one edge is held in contact with the 45 upper surface of the table B by the pressure of the spiral springs F⁷, so the side F¹⁰ of the roll next the first scoring mechanism will serve as a stop for the advancing edge of the cardboard. Upon the gudgeon F³ is pivoted 50 a swinging frame G, slotted at its lower end at G' to receive a swinging block G², pivoted at G³ with its axis at right angles with the axis of the swinging frame 1. The lower end of the swinging block G² carries a stud G⁴, upon 55 which is journaled a beveled roll G⁵, presenting a sharp corner G⁶ to the surface of the table B. As the sheet of cardboard is moved against the stop-roll F⁹ in the direction of the arrow G⁷, Fig. 7, the retaining-roll G⁵ is raised 60 by the swinging of the block G², allowing the cardboard to pass beneath the retaining-roll, allowing the sharp corner G⁶ to rest upon the

upper surface of the cardboard and by its engagement with the cardboard prevent its rebound or backward movement. As the cardboard is pushed toward the second scoring mechanism by the pusher-plate B²³ the forward end of the cardboard is in contact with the stop-roll F⁹ and its upper surface is engaged by the sharp corner G⁶ of the retaining-roll G⁵, and both the stop-roll F⁹ and the retaining-roll G⁵ are free to move in the direction of the moving cardboard by the rotation of their swinging frames F⁴ and G upon their supporting-gudgeons. By this means I 70 avoid any friction between the edge of the cardboard and the side of the retaining-roll and prevent any displacement of the cardboard owing to the movement of an irregular edge against the side of the stop-roll F⁹, in 75 order to allow the pushing-plate B²³ to pass under the rolls carried by the swing-frame, if required, but if not then to allow the frame to swing as the sheet of cardboard is moved along by the forward motion of the pushing-80 plate and prevent any undue friction or drag upon the sheet of cardboard.

As it bears against the side of the roll F⁹, the stop device above described can be adjusted to any position upon the surface of the 85 second feed-table B by sliding the sleeves E' E' on the parallel rods E E and by moving the sleeve F on the cross-rod E². The rotating cutters employed in each of the scoring mechanisms are alike and are represented in Figs. 90 8, 9, and 10.

The cutters consist of a disk H, provided with a knife-edge turning upon a stud H', held in a slotted yoke H², which is pivoted at one end to one end of a link H³, the opposite end of the link being pivoted to a frame H⁴, which is adjustably attached by a screw H⁵ to the cutter-bar. By connecting the yoke to the frame by the link H³, I cause the end of the yoke to move in the arc of a circle as it is 105 moved down, said arc nearly coinciding with a straight line. The opposite end of the yoke H² slides in ways in the frame H⁴, and the frame H⁴ carries a set-screw H⁶, provided at its inner end with a neck H⁷ and head H⁸, engaging a T-slot in the end of the yoke H², by which the yoke is moved up or down in its ways by the screw H⁶. The end of the yoke sliding in the ways of the frame H⁴ is held in position by a plate H⁹, attached to the frame 110 H⁴ by a screw H¹⁰, and between the plate H⁹ and end of the yoke I interpose a spring H¹¹ in order to take up any lost motion between the yoke and its ways. The spring H¹¹ also allows a slight movement of the yoke as it is 115 acted upon by the link H³.

One of the gudgeons A¹⁴ of the pressure-plate A¹³ is squared at its outer end, as at I, to receive a plate J, which is held upon the squared end of the gudgeon by a screw J'; so 120 the plate J will turn with the gudgeon. The plate J carries a pin J², which enters a slot J³ in the tailpiece A¹⁷ in order to limit the downward movement of the edge A²⁰ of the

pressure-plate as the cardboard passes beneath it.

What I claim as my invention, and desire to secure by Letters Patent, is—

- 5 1. In a scoring-machine the combination with the feed-table of an angle-plate attached to said table at one side thereof and adjustable on said table in a line at right angles with the movement of the cardboard and having a vertical member forming a rail parallel with the movement of the cardboard on said table, a plate inclosing the upper edge of said rail and capable of sliding thereon, and a pushing-plate projecting from the side of said 15 sliding plate and extending across the table, substantially as described.
2. In a scoring-machine, the combination with a feed-table and a bed-roll of a yielding pressure-plate provided with gudgeons pivoted in removable sleeves held in the forked framework of the machine, an adjustable collar attached to one of said gudgeons and a torsional spring carried by said adjustable collar and engaging one of said sleeves, tail- 25 pieces projecting from said sleeves, and adjusting-screws bearing against said tailpieces by which said sleeves are rocked in the framework, in order to adjust the position of said pressure-plate, substantially as described.
3. In a scoring-machine, the combination, with a feed-table, of a pair of rods supported above the feed-table and parallel therewith, clamping-bars adjustably attached to said rods, retaining-plates supported over said 35 clamping-bars a short distance above and parallel with the surface of the feed-table, and means for imparting a downward-yielding pressure to said retaining-plates, substantially as described.
4. In a scoring-machine, the combination with a table and a scoring mechanism by which a sheet of cardboard is delivered on said table, of an arm suspended vertically above said table and capable of a swinging motion about an axis parallel with the movement of the cardboard upon said table as it is delivered thereon by said scoring mechanism and a roll journaled in the lower end of said arm with its side presented to the edge 50 of the advancing sheet of cardboard, substantially as described.

5. In a scoring-machine, the combination with a table and a scoring mechanism by which a sheet of cardboard is delivered upon said table, of a swinging frame suspended above said table, a roll held in the lower end of said frame and presenting its side to the advancing edge of cardboard, and a spring by which the face of said roll is held against 55 the surface of said table, substantially as described.

6. In a scoring-machine, the combination with a table on which the sheet of cardboard is delivered by the scoring mechanism, of a 60 rod supported above said table and extending across the same, a sleeve adjustably attached to said rod, a swinging frame suspended ver-

tically from said frame, and a roll carried by said swinging frame with its face in contact with said table and its side presented to the advancing edge of the cardboard, substantially as described.

7. In a scoring mechanism the combination with a feed-table upon which the cardboard is fed by the scoring mechanism of a stop by which the forward motion of a sheet on said feed-table is limited, a swinging frame suspended vertically above said table and in front of said stop, and a beveled roll supported by said swinging frame with its edge adapted to engage a sheet of cardboard lying on said table, substantially as described.

8. The combination with the feed-table B of a swinging frame suspended above said feed-table, a block pivoted in said swinging frame with its axis at right angles with the axis of said swinging frame, and a beveled roll carried by said swinging block with its edge adapted to engage a sheet of cardboard lying on said table, substantially as de- 90 scribed.

9. In a scoring-machine the combination with a feed-table B and a rotating scoring-roll A⁶ of guide-plates attached to the edge of said table and extending over said scoring- 95 roll, whereby the severed edges of a sheet of cardboard are deflected below said feed-table, and blades projecting laterally from the sides of said guide-plates and in the horizontal plane of said table, whereby the edges of the 100 cardboard are supported.

10. In a scoring-machine, the combination with a table and mechanism by which a sheet of cardboard is fed upon said table of a pushing mechanism having an intermittent reciprocating motion, a clutching mechanism by which said pushing mechanism is connected at will with the driving power, a pivoted finger with its end hanging in the path of a sheet of cardboard as it is fed upon said table, 105 means for reversing the motion of said finger after the sheet of cardboard has passed beneath it, and mechanism by which said finger is operatively connected with said clutching mechanism to operate the same on the reverse movement of said finger, substantially 110 as described.

11. In a scoring mechanism the combination with a feed-table B of a pivoted finger hanging in the path of a cardboard as it is 115 moved upon said feed-table, a pivoted lever C⁴ operatively connected at one end with said pivoted finger by which said lever is rocked by the movement of said finger, a spring attached to said lever to reverse its motion, a vertical rod C⁶ pivoted at one end to the opposite end of said lever, toggle-joint levers connecting the opposite end of said vertical rod with the frame of the machine, whereby 120 said rod is given a lateral motion at each vertical movement, a shoulder on said vertical rod C⁶ adapted to engage a pivoted latch and raise the same, a clutching mechanism arranged to be released by the raising of said 125

latch, a pushing-plate, means for actuating said plate, comprising said clutching mechanism, substantially as described.

12. In a scoring-machine the combination 5 with a feed-table provided with a guideway at its side of a sliding plate sliding in said guideway, means for imparting an intermittent motion to said sliding plate and a pusher-plate consisting of a flat blade lying in the 10 plane parallel with the face of said feed-table and attached at one end to said sliding plate and projecting over said table, substantially as described.

13. In a scoring-machine, the combination, 15 with a feed-table provided with a guideway at its side, of a sliding plate sliding in said guideway, means for imparting an intermittent motion to said sliding plate, a retaining-plate held at a slight distance above the 20 face of said feed-table and parallel therewith, and a pusher-plate attached at one end to said sliding plate and consisting of a flat

blade capable of a reciprocating motion in a space between said feed-table and said retaining-plate, substantially as described. 25

14. In a rotary cutter and a scoring-machine, the combination of a frame H^4 , a yoke H^2 , a rotating cutter carried by said yoke, a link pivoted at one end to said frame and at the opposite end to one end of said yoke 30 whereby the movement of the pivoted end of the yoke is controlled in the arc of a circle, the opposite end of said yoke being inclosed in a yielding guideway carried by said frame and capable of sliding therein, and an adjusting-screw bearing against the end of said yoke inclosed in said guideway, substantially as described. 35

Dated this 8th day of April, 1896.
